US00D902250S

(12) **United States Design Patent** (10) Patent No.: **US D902,250 S**
(45) Date of Patent: ** *Nov. 17, 2020

(54) **DISPLAY SCREEN OR PORTION THEREOF WITH ICON**

(71) Applicant: **Apple Inc.**, Cupertino, CA (US)

(72) Inventors: **Kevin Will Chen**, Cupertino, CA (US); **Alan C. Dye**, San Francisco, CA (US); **Jonathan P. Ive**, San Francisco, CA (US); **Christopher Wilson**, San Francisco, CA (US); **Eric Lance Wilson**, San Jose, CA (US)

(73) Assignee: **Apple Inc.**, Cupertino, CA (US)

(*) Notice: This patent is subject to a terminal disclaimer.

(**) Term: **15 Years**

(21) Appl. No.: **29/733,390**

(22) Filed: **May 1, 2020**

CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is a second embodiment thereof.

The broken lines in the figures show a display screen or portion thereof, and form no part of the claimed design.

**1 Claim, 2 Drawing Sheets
